UNITED STATES PATENT OFFICE.

JOHN H. PARMELEE, OF BRIDGEPORT, CONNECTICUT.

DESIGN FOR A TOY MONEY-BANK.

SPECIFICATION forming part of Design No. 13,016, dated June 27, 1882.

Application filed April 8, 1882. Term of patent 3½ years.

To all whom it may concern:

Be it known that I, JOHN H. PARMELEE, a citizen of the United States, residing at Bridgeport, in the county of Fairfield and State of Connecticut, have invented a certain new and useful Design for Toy Money-Banks, of which the following is a specification, reference being had therein to the accompanying drawing, which shows a sea-shell in elevation and mounted upon a standard.

I have shown my design in the shape of a sea-shell with a standard or base.

What I claim as new, and desire to secure by Letters Patent, is—

As a design for a toy money-bank, a sea-shell provided with a standard or base, substantially as and for the purpose set forth.

In testimony whereof I affix my signature in presence of two witnesses.

JOHN H. PARMELEE.

Witnesses:

JOSEPH A. JOYCE,
W. T. HAVILAND.
